EVAPORATIVE COOLING ATTACHMENT FOR ELECTRIC FANS

Robert J. Curran, Kansas City, Mo.

Application September 13, 1954, Serial No. 32,247

Term of patent 3½ years

(Cl. D62—4)

Fig. 1.

Fig. 2.

To all whom it may concern:

Be it known that I, Robert J. Curran, a citizen of the United States, residing at Kansas City, in the county of Jackson and State of Missouri, have invented a new, original, and ornamental Design for an Evaporative Cooling Attachment for Electric Fans, of which the following is a specification, reference being had to the accompanying drawing forming a part thereof.

Fig. 1 is a perspective view of an evaporative cooling attachment for electric fans, showing my new design and illustrating the same in the operative position; and

Fig. 2 is a rear perspective view thereof illustrating the same completely removed from the normal operative position.

The portions in broken lines are for purpose of illustration.

I claim:

The ornamental design for an evaporative cooling attachment for electric fans, as shown and described.

No references cited.
